UNITED STATES PATENT OFFICE.

LOUIS BURGER, OF CHICAGO, ILLINOIS.

DESIGN FOR A SPOON.

SPECIFICATION forming part of Design No. 22,255, dated March 7, 1893.

Application filed January 3, 1893. Serial No. 457,171. Term of patent 3½ years.

To all whom it may concern:

Be it known that I, LOUIS BURGER, a citizen of the United States, residing at Chicago, county of Cook, and State of Illinois, have invented and produced a new and original Design for the Handles of Souvenir Spoons, &c., of which the following is a specification, reference being had to the accompanying drawing, which is a fair illustration thereof.

10 The leading feature of my design consists in a handle portion, the head or terminal of which is given the outline of a medallion of Columbus with unfurled flags about it, adjacent to which medallion appears a shield having stars in its upper part and a picture upon it representing the departure of Columbus for

15

the New World. The remainder of the shank of the handle, meaning that between the shield and the bowl, is given an embossed outline with a caryatides adjacent to the shield between which caryatides is a smaller shield divided into three spaces. 20

What I claim as new, and desire to secure by Letters Patent, is—

The design for the handle of a souvenir spoon &c., substantially as shown and described. 25

LOUIS BURGER.

In presence of—

J. N. HANSON,
W. N. WILLIAMS.
